UNITED STATES PATENT OFFICE.

HENRY HANSEN, OF CHICAGO, ILLINOIS, ASSIGNOR TO JAY M. JOHNSON, OF CHICAGO, ILLINOIS.

DESIGN FOR A CORNER-POST SPOTLIGHT.

Application filed October 13, 1926. Serial No. 19,315. Term of patent 3½ years.

To all whom it may concern:

Be it known that I, HENRY HANSEN, a citizen of the United States, residing at Chicago, in the county of Cook and State of Illinois, have invented a new, original, and ornamental Design for Corner-Post Spotlight, of which the following is a specification, reference being had to the accompanying drawings, forming a part thereof.

On the drawings:

Fig. 2 is a front view thereof; and

Fig. 3 is a rear view thereof.

I claim:

The ornamental design for a corner post spotlight, as shown.

HENRY HANSEN.
